OF DES MOINES, IOWA, A CORPORATION OF IOWA.

ROOFING ELEMENT.

Application filed November 2, 1925. Serial No. 33,917.

The object of this invention is to provide an improved construction for roofing elements including flexible roof covering means and interlocking means therefor.

6 A further object of this invention is to provide improved means for locking together and holding to a roof asphalt or composition shingles or strips.

10 Another object of this invention is to provide an improved hook member adapted to be attached to the lower marginal edge of one shingle or element and to engage the edge of a subjacent member when laid on a roof.

15 Still another object is to provide an improved hook member of such shape as to facilitate the laying of shingles or roofing elements in superposed position on a roof, by furnishing guides to cause the members to move to their proper positions.

20 Another object is to so arrange the hooked member relative to the margin of the flexible element to which it is attached as to insure uniform expansion and contraction 25 of the flexible element with changes of temperature and thus prevent breaking of a turned edge.

25 A further object is to provide simple and economical means for obtaining an efficient 30 roof covering which is capable of resisting entrance of sleet, snow, rain and wind between the roofing elements.

35 With these and other objects in view, my invention consists in the construction, arrangement and combination of elements hereinafter set forth, pointed out in the claims and illustrated by the accompanying drawing, in which—

40 Figure 1 is a plan view showing a section of roofing constructed according to my invention.

45 Figure 2 is a perspective view showing the under side of one of the roofing elements and its interlocking hook member.

50 Figure 3 is a section on the line 3—3 of Figure 1.

55 Figure 4 is an enlarged section on the line 4—4 of Figure 1.

60 Figure 5 is a perspective view of one of the hook members detached.

65 Figures 6 and 7 are plan and end views respectively of the hook member shown in Figure 5.

70 In carrying out my invention I employ a

flexible or semi-flexible element or body 55 member 10, which may be an individual or a strip shingle made in a common way of a suitable combination of paper, rags, asphalt and the like, and it may be of fire-proof construction. The shingle body 10 may be 60 straight along its upper margin, but its lower margin is formed with a plurality of spaced projections 11 separated by notches 12 of substantially the same width. The projections 11 on a shingle body 10 may be 65 of any desired number and will depend upon the length of said body when the shingle is of strip form as shown; and in any event the joint between shingles in the same row would come at about the middle 70 of a notch 12, which would also be the case where the shingles are of individual or single form. The projections and notches may be of any desired depth but said notches preferably are not extended past the center 75 of the shingle.

Fixed to the lower margin of each projection 11 is a metallic clip or fastening member 13 which is of a length corresponding substantially to the width of the end 80 of the projection. Each clip 13 is formed with a row of teeth 14 struck therefrom and projecting upwardly and also with a similar row of teeth 15 projecting downwardly. The end marginal portion of 85 the projection 11 is bent or folded under to embrace the outer edge of the clip 13 and the teeth 14 and 15 are caused respectively to penetrate the body of said projection adjacent the fold, and the folded 90 under portion which has been designated 16, and said teeth are clenched to effectively grip the shingle material. The projection of teeth in both directions into and through the shingle material tends to prevent any 95 relative movement of the folded portion relative to the body, such as expansion and contraction which might be caused by changes of temperature, and thus, by insuring uniform expansion and contraction, prevents 100 any cracking or breaking of the material at the fold or bend. Intermediate of its width the clip 13 is offset at 17, on a longitudinal line, a distance substantially equal to the thickness of the shingle, thus forming hooks 105 18 which are spaced downwardly from the adjacent portion of the projection 11 when in normal position. In this instance I have

shown two hooks 18 each of somewhat less than one-half the length of the clip 13 and spaced apart at the center of the clip by a portion 19 which is severed on parallel lines 5 and again bent back upwardly, adjacent the center of the offset 17, to the plane of the body of the clip. If desired more than two hooks 18 may be employed, similarly spaced apart. The bent up portion 19 has a function which will later be made clear, and it is provided with teeth 20 struck upwardly therefrom and penetrating the shingle material.

In practical use successive rows or strips 15 are laid as in Figure 1 in overlapping relation and with the projections and notches of adjacent rows or strips in staggered relation. A nail such as 21 is driven through each shingle or strip 10 adjacent the center 20 of each notch 12 and spaced suitably from the margin thereof. The clip 13 of each projection 11 is caused to engage the rear margin of a notch 12 of the subjacent row or strip 10 in the manner shown, to hold 25 the end of the projection tight to the roof. The projections 11 preferably are of slightly less width at the free end than where they are attached to the body of the shingle, and consequently the notches 12 are of slightly 30 greater width at their open than at the closed end, the side margins sloping uniformly and symmetrically. The superposed shingle or strip is placed in position by inserting the ends of the projections 11 35 in the notches 12 near the open end of the latter and moving them rearwardly until the clips 13 engage the side margins of the notches. The clips 13 are formed with laterally opening notches 22, 23 cut from the 40 ends of the offset portion 17, which notches 22 and 23 engage and receive the side margins of the projections 11 of the subjacent row as the strip being placed is drawn rearwardly, or upwardly of the roof. This 45 movement is continued until the hooks 18 engage and embrace the shingle at the inner end of the notch 12, and are guided to this position by the engagement of the lateral notches 22 and 23 with the sides of the notch 12. The hooks 18 preferably are of greater 50 width at their outer ends than at the inner, such wider portions being guided to engagement with the body portion of the shingle because of the previous engagement of the 55 lateral notches 22, 23, and in turn guiding the remaining portions of the hooks to engagement with said body because of the sloping margins. This facilitates the engagement of the hooks in case there has been 60 any bending either of the hooks or of the margin of the shingle at the inner end of the notch 12. Preferably the hooks 18 are slightly concavo-convex in cross-section, with the convex surface directed upwardly, 65 which not only strengthens the hooks, and

causes a greater frictional grip on the part engaged, but also tends to prevent mashing of the hooks in transportation or handling them, either singly or in bundles. The bent-up portions 19 between the hooks overlie 70 the heads of the nails 21 and prevent their contacting with the body of the superposed shingle or being pushed through the same; and in case more than one bent-up portion 19 is provided for each clip, then a similar 75 number of nails would be employed adjacent each notch 12. This would be advisable in the event the notches 12 and projections 11 are of considerable width.

The doubled under edge of the projections 11 are held by the hooked clips 13 in close contact with the shingle at the inner ends of the notches 12, which are in turn held close to the roof by the nails 21. This tends to prevent the entrance of rain or other weather elements between the shingles, and in hot weather some of the plastic material of the shingle melts somewhat and seals the joints between the closely held adjacent shingles, thus making a very tight roof covering. 80 It is apparent that at the corners of the notches, the shingle is held between two metal parts because of the lateral notches 22 and 23, and in hot weather these metal parts become imbedded in the material of 85 the shingle and form a further seal against the weather. As before stated, the double gripping of the end of the projections 11 by teeth extending in both directions prevents a breaking of the folded portion, 90 which because of its thickness forms a good joint not apt to be lifted from the roof. The clip 13 being enfolded between two thicknesses of shingle material and being 95 underneath the projection 11 is prevented 100 from rusting.

Other advantages of this improved roofing element will be understood by those skilled in the art. For instance, this improved roofing element with its interlocking means is so efficient in excluding the weather that it is adapted for use on roofs which are flat or have but slight pitch.

I claim as my invention—

1. A roofing element comprising a body 115 formed on one margin with alternating projections and notches, each roofing element adapted to receive one or more nails adjacent the inner end of each notch, a clip fixed to the bottom side of each projection at its 120 end and offset to form hooks adapted to engage the inner end of a notch of a subjacent element, a portion between the hooks of each clip being bent back to the plane of the clip to overlie the head of each nail in the subjacent element.

2. A roofing element comprising a body formed on one margin with alternate projections and notches, a clip underlying the end portion of each projection and offset to 130

- form hooks, said clip being formed with teeth extending in both directions from its body, the end portion of the projection being folded around the margin of the clip and the teeth of the clip penetrating in both directions the material of the said projection to cause uniform expansion and contraction thereof.
3. A roofing element comprising a body formed on one margin with alternating projections and notches, a clip underlying the end portion of each projection and offset to form hooks, said hooks being concavo-convex in cross-section and also being of greater width at their outer than at their inner ends. 15
4. An interlocking means for a roofing element comprising a clip offset between its sides to form one or more hooks, the offset portion of said clip being formed with laterally opening notches at its ends, the hooks being slightly concavo-convex in cross-section with the convex surface arranged upwardly toward the plane of the body of the clip. 20

ISADORE DAVIS.
